Primary Examiner — Michelle E. Wilson(74) *Attorney, Agent, or Firm* — Bush Intellectual Property Law; Kenneth M. Bush(57) **CLAIM**

I claim the ornamental design for a dryer ball, as shown and described.

DESCRIPTION

FIG. 1 is a top, front, right side perspective view of a dryer ball showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings represent portions of the dryer ball that form no part of the claimed design.
